UNITED STATES PATENT OFFICE.

FRANK A. BOYD, OF NEW ROCHELLE, NEW YORK.

ROTARY ENGINE.

SPECIFICATION forming part of Letters Patent No. 600,710, dated March 15, 1898.

Application filed March 10, 1897. Serial No. 626,783. (No model.)

To all whom it may concern:

Be it known that I, FRANK ALPHEUS BOYD, of New Rochelle, in the county of Westchester and State of New York, have invented new and useful Improvements in Rotary Engines, of which the following is a full, clear, and exact description.

This invention relates to rotary engines adapted to be actuated for development of rotary motion and power by steam, compressed air, or water under pressure used as a motive agent.

The object of the invention is to provide novel features of construction for an engine of the indicated character which are simple, efficient, not liable to derangement of working parts in service, and which are capable of utilizing the motive agent to great advantage.

The invention consists in the special construction and combination of parts, as is hereinafter described, and defined in the claim.

Reference is to be had to the accompanying drawings, forming a part of this specification, in which similar characters of reference indicate corresponding parts in all the figures.

Figure 1 is a sectional side view of the improved rotary engine substantially on the line 1 1 in Fig. 3. Fig. 2 is an exterior side view of the nozzle-supporting block and a portion 30 of the bucket-wheel case, seen in direction of arrow α in Fig. 6. Fig. 3 is a transverse sectional view of the engine substantially on the line 3 3 in Fig. 1. Fig. 4 is an enlarged transverse sectional view of the exhaust-nozzle for the engine and of adjacent parts essentially on the line 4 4 in Fig. 1. Fig. 5 is an enlarged transverse sectional view of the adjustable bracket-block and other parts of the engine engaged therewith, taken, essentially, 40 on the line 5 5 in Fig. 1. Fig. 6 is an enlarged transverse sectional view, on the line 6 6 of Fig. 1, of the adjustable bracket-block, the induction-nozzle therein, and other parts of the engine adjacent to said details; and Fig. 45 7 is a transverse sectional view taken, substantially, on the line 7 7 in Fig. 1.

A suitable casing 10 is provided which is adapted for support on a base 11, and said casing may be cylindrical, as shown, or of 50 other construction. On pedestal-blocks 12 or equivalent supports that are erected upon

the base 11 the horizontal driving-shaft 13 is rotatably supported, either by the means shown or in any other preferred manner, which shaft projects at each side of the casing 10, as shown in Fig. 3, and may be provided with the pulleys 13^a. On the driving-shaft 13 within the casing 10 the circular bucket-wheel 14 is mounted and secured.

The wheel 14 comprises a disk that is provided with a center hub a , which is affixed to the shaft 13, as before indicated, and on the periphery of the disk, that is of a predetermined breadth of face proportioned to the capacity of the engine, a continuous series of buckets b is formed. The similar buckets b each consist of a transversely-disposed flange having one face or abutment b' slightly undercut, as shown in Fig. 1, and the other wall b^2 of the bucket sloped to approach the base 70 of the next abutment b' in sequence, thus producing a continuous series of spaced angular buckets around the circumference of the wheel 14 that are essentially ratchet-toothed in form. At each side of the wheel 14 a track-ring 15 is secured, preferably with bolts and nuts that hold both of the rings in position, as shown in Figs. 1 and 3.

Each of the track-rings 15 has its periphery V-grooved for a purpose which will presently 80 be explained.

The bucket-wheel 14 is preferably located eccentrically within the casing 10, as shown in Fig. 1, and the latter may have openings c and d , respectively, at the upper and lower 85 sides of the peripheral wall of the same, the use of which will be hereinafter described. In the wider space that intervenes the inner surface of the casing 10 and the periphery of the bucket-wheel a bracket-block 16 is introduced. The bracket-block 16 has its face that is nearest to the periphery of the bucket-wheel 14 rendered concave, representing the arc of a circle, the radial center of which is in the axis of the shaft 13, and is thus adapted 90 to have a fluid or liquid tight contact with the periphery of the bucket-wheel.

On the outer and convex side of the bracket-block 16 projecting portions g h are formed to receive bolts i , that pass through lugs g' h' , 100 which latter extend from the inner side of the casing 10, and the bolt-holes in these lugs

are somewhat elongated to permit an adjustment of the bracket-block toward or from the bucket-wheel by means of the set-screw *k*, which is screwed through the casing 10.

5 On each side of the bracket-block 16 like segmental plates 17 are secured by the transverse bolts *l*, and a packing-joint 18 is preferably introduced between each side plate 17 and the adjacent side wall of the bracket-block, as shown in Figs. 1, 2, 5, and 6, to prevent leakage from the buckets of the wheel 14.

The concave edges of the segmental side plates 17 are beveled to adapt each plate to enter its angular or V-shaped edge within the

15 V-shaped groove in the track-ring 15 it is directly opposite. As represented in Figs. 1 and 5, the bolt-holes in the side plates 17 are sufficiently enlarged to permit an adjustment of the side plates edgewise toward the grooved 20 edges of the track-rings 15, so as to bed their angular edges steam or liquid tight in said grooves.

To conveniently effect the inward movement of the side plates 17 on the bracket-block 16 and their retention when adjusted edgewise, set-screw bolts *m* are provided, which have a threaded engagement with the perforated laterally-projecting ears *m'* on the sides of the bracket-block near its outer face, 30 which set-screws bear upon the outer edges of the side plates and facilitate a graduation of pressure therefor upon the grooved peripheries of the track-rings 15.

The bracket-block 16 is recessed on the concave side to receive a facing or packing strip 35 16^a of metal or other suitable material, which will form a durable and tight joint where it contacts with the periphery of the bucket-wheel 14, and said engagement of the facing-strip with the bucket-wheel is adjusted for pressure by the set-screw bolts *n* and nuts *n'* thereon, as best shown in Fig. 6.

It will be seen in the figure mentioned that the ends *n*² of the bolts *n*, which are in contact with the facing-strip 16^a, are circumferentially grooved, so as to have a swiveled engagement therewith, whereby the bolts are adapted to withdraw the packing-strip, as well as press it toward the bucket-wheel, and 50 thus enable an exact adjustment of the strip to be manually effected.

In the bracket-block 16, preferably near the lower transverse edge of the facing-strip 16^a, a fluid or liquid induction nozzle 19 is formed by production of a converged passage diagonally therein, and this induction-passage, that projects downwardly and inwardly, as shown in Fig. 1, is provided with an adjustable gate 20, which is held by one end in 55 a depression within the nozzle-passage, as shown at *o* in the figure mentioned. The gate 20 is formed of spring metal, such as brass, and is adapted to yield to pressure on its free end, so as to move said end toward 60 the opposite side of the nozzle-passage and thus contract its area, the resilience of the gate returning the same to a normal position

when the pressure is relaxed. The preferred means for effecting the adjustment of the gate 20 consists of the screw-bolt 21, which passes through a packed orifice in the bracket-block 16, so as to bear upon the gate.

The outer end of the set-bolt 21 is loosely passed through a perforation in the casing 10, but is held at a desired point of longitudinal 75 adjustment by the jam-nuts *p*, one of which is located in a slot formed in a projection from the wall of the casing, so as to bear thereon oppositely from the other jam-nut, that is seated upon the exterior of said projection, 80 as is clearly shown in Figs. 1 and 7.

In the perforation of the casing 10 a tubular conduit 22 for the fluid or liquid motive agent, such as steam or water, is inserted and inclines toward the upper end of the diagonally-trending nozzle-passage 19, into which this end of the pipe is screwed or otherwise secured, said pipe or conduit in completed form being extended to a steam-generator or a source of air or water under pressure for 90 supplying the preferred motive agent to the engine.

At a point near the lower extremity of the bracket-block 16 an exhaust-channel *r* is formed, wherein the spring-gate 23 is held at 95 the inner end thereof by a screw-bolt *s*. An adjusting-bolt 24 is inserted through a looped projection *t* on the casing 10 and thence through an orifice in said casing, the inner end of the bolt extending through an aligned 100 perforation in the bracket-block 16, so as to press upon the gate 23.

The bolt 24 is provided with two jam-nuts *t*, that respectively engage the inner and outer sides of the looped projection *t* and thus afford 105 means for graduating the pressure of the bolt upon the gate 23 as may be desired.

The nozzle-passage 19 and channel *r* are of the same width and each is rectangular in cross-section, said formations in the bracket-block 16 being merged together by the intervening channel *u*, which, as is shown in Fig. 1, gradually diminishes in depth to a point midway between the nozzle 19 and exhaust-channel *r*. Preferably a small tube 25 is inserted through a hole in the casing 10 toward the upper end of the facing-strip 18 for supplying a lubricant thereto, as shown in Fig. 1.

If the engine is to be used as a water-motor, water under pressure is conveyed through the supply-pipe 22 to the nozzle 19, and the force of the water-jet is exerted on the buckets *b*, that lie between the exit-orifice of the nozzle and the inlet to the exhaust passage or channel *r*.

It will be seen that the contraction of the channel *u*, which extends between the nozzle 19 and exhaust-channel *r*, serves to enforce a contact of the liquid motive agent with the abutments *b'* on the buckets *b* of the wheel 14, so that the full pressure of the water will be exerted for rotation of said wheel. The provision of means for the graduation of the area of the nozzle 19 and exhaust-channel *r*,

as hereinbefore described, enables the adjustment of said parts to suit the initial pressure or force exerted by the motive agent, and thus utilize said force economically and to obtain 5 the best results per cubic foot of liquid passed through the engine.

The opening *d* in the lower side of the casing 10 is to be connected with a sewer by a pipe *d'* (shown broken in Figs. 1 and 3) to carry 10 away the water that has passed through the engine, and in case air or steam is the motive agent the aperture *d* may be used to carry off water resulting from the condensation of steam, while the upper orifice *c* takes away 15 the air or exhaust-steam.

It is evident that, if desired, the apparatus which has been described may be duplicated for a large engine to apply the motive agent to two portions of the bucket-wheel simultaneously and thus increase power developed 20 by the engine.

Having thus described my invention, I

claim as new and desire to secure by Letters Patent—

In a rotary engine, the combination with 25 a casing, a bucket-wheel therein, a transverse driving-shaft on which the bucket-wheel is secured, and track-rings secured on sides of the bucket-wheel near its periphery, said rings having V-grooves in their outer edges, 30 of an adjustable concave-faced bracket-block supported from the casing, adjustable side plates on the bracket-block, an induction-passage, and an exhaust-passage being formed in the bracket-block and having communication with the buckets of the wheel, and an adjustable gate in the said induction-passage, and in the exhaust-passage, as specified. 35

FRANK A. BOYD.
